G. C. CLANTON,
WALL RADIATOR BRACKET,
APPLICATION FILED AUG. 3, 1921.

1,422,177.

Patented July 11, 1922.

Inventor
Grover C. Clanton
By his Attorney
Mr. Wallace White

UNITED STATES PATENT OFFICE.

GROVER C. CLANTON, OF BAYONNE, NEW JERSEY.

WALL-RADIATOR BRACKET.

1,422,177.

Specification of Letters Patent. Patented July 11, 1922.

Application filed August 3, 1921. Serial No. 489,449.

To all whom it may concern:

Be it known that I, GROVER C. CLANTON, a citizen of the United States of America, residing at Bayonne, county of Hudson, and 5 State of New Jersey, have invented new and useful Improvements in Wall-Radiator Brackets, of which the following is a specification.

The object of my invention is to provide 10 a bracket or support for radiators of the wall and legless type, and which is capable of three adjustments, one vertical and two horizontal at right angles to each other, which is easy to install and which at the 15 same time is practically concealed from view.

The invention is inexpensive to manufacture, substantial in construction and reliable in operation.

20 In the accompanying drawings forming part of the specification which illustrates a preferred embodiment of the invention, Figure 1 shows a side elevation of a wall steam radiator supported by the improved brackets, only one of which is shown, and Fig. 2 shows, in perspective, the two sections comprising the bracket, bolted together.

Referring now to the drawings, in Fig. 1 30 there is shown a bracket whose flanged portion, 1, is secured to a wall, 7, and supports a radiator, 9, whose bosses, 10, between two adjacent sections of the radiator, rest upon the curved section, 3, of the 35 bracket.

The bracket consists of two pieces of 40 heavy sheet iron or other metal, 1 and 2. The part 1 is of substantially rectangular form, bent at right angles and has vertical and horizontal slots, 5, 4, or a series of 45 holes; while the other member 2, of the bracket consists of a triangular-shaped piece of similar metal and is also provided with horizontal slots or holes, 6, and a curved notch, 3, adjacent its outer and upper edge, which supports the radiator.

The bent or flanged portion, 1, of the bracket is secured to the wall, 7, by lag screws or bolts, 8, and the other member, 50 2, of the bracket is fastened to the first-mentioned portion by bolts 11, 12, and the

radiator 9 is hung upon the curved or notched portion 3, supporting the radiator which rests upon bosses between adjoining sections of the radiator.

55 While for purposes of illustration I have shown a steam radiator, it will be understood that the bracket is adapted for use with any form of wall or of the legless type of steam or hot water radiators in use; and 60 the form of the curved section 3 of the bracket may be variously modified to suit any type of radiator without departing from the spirit of my invention.

It will be readily understood that by 65 means of the slots or series of holes in the bracket, adjustment in a vertical or horizontal direction and also toward and away from the wall or other support to which the radiator is attached is provided for, rendering much more convenient the operation 70 of installing radiators.

Having now described my invention, what I claim is:

1. A radiator support, comprising a wall 75 member formed of a pair of sheet metal flanges disposed at right-angles to each other and provided with a plurality of elongated slots, and a sheet metal member removably secured to one of said flanges and adapted 80 to support a radiator, said last member being provided with elongated slots disposed at right-angles to and intersecting the slots of the flange to which it is secured, thereby to permit adjustment of the radiator in two 85 directions, the slots of the remaining flange of the wall member being disposed so as to permit adjustment of the radiator in a third direction.

2. A radiator support, comprising a wall 90 member formed of a pair of sheet metal flanges disposed at right-angles to each other, one of said flanges being provided with horizontally extending slots and the other with vertically extending slots, and a 95 radiator support removably secured to the vertically slotted flange and provided with horizontally extending slots intersecting the slots of said flange.

In testimony whereof I have signed my 100 name to this specification.

GROVER C. CLANTON.
